[57] CLAIM

The ornamental design for an aquarium cleaner, as shown and described.

DESCRIPTION

FIG. 1 is a perspective view of an aquarium cleaner embodying my new design;

FIG. 2 is a front elevational view thereof;

FIG. 3 is a rear elevational view thereof;

FIG. 4 is a left side elevational thereof;

FIG. 5 is a right side elevational thereof;

FIG. 6 is a top plan view thereof;

FIG. 7 is a bottom plan view thereof;

FIG. 8 is a sectional view taken along the line 8—8 of FIG. 6; and

FIG. 9 is a front elevational view thereof on a slightly reduced scale, showing a state in which the filter section is angularly displaced.

The cross-hatching which is partially shown for ease of illustration on the filter bag in FIGS. 1, 2, 3, 5 and 7, represents a conventional fabric and is understood to cover the entire bag.
